(57) **CLAIM**

The ornamental design for a wheel drying brush, as shown and described.

DESCRIPTION

FIG. 1 is a top plan view thereof;

FIG. 2 is a bottom plan view thereof;

FIG. 3 is a left side view thereof;

FIG. 4 is a right side view thereof;

FIG. 5 is a front elevational view thereof;

FIG. 6 is a rear elevational view thereof; and,

FIG. 7 is a perspective view of our new design for a wheel drying brush, the handle being illustrated in broken lines for environmental purposes only and forming no part of the claimed design.
